MIXED GLYCEROL ESTERS AND THEIR
ACYLATION PRODUCTS

Edward M. Filachione, Philadelphia, Pa., Martin L. Fein, Riverside, N. J., and Charles H. Fisher, Abington, Pa., assignors to United States of America as represented by the Secretary of Agriculture

No Drawing. Application June 18, 1948,
Serial No. 33,839

14 Claims. (Cl. 260—410.8)

(Granted under the act of March 3, 1883, as
amended April 30, 1928; 370 O. G. 757)

1

This application is made under the act of March 3, 1883, as amended by the act of April 30, 1928, and the invention herein described and claimed, if patented in any country, may be manufactured and used by or for the Government of the United States of America for governmental purposes throughout the world without the payment to us of any royalty thereon.

This application is a continuation-in-part of our copending application for patent, Serial No. 770,179, filed August 22, 1947, now Patent No. 2,534,255, the disclosure of which is incorporated herein by reference.

This invention relates to glycerol esters, more particularly to mixed glyceryl esters of aliphatic hydroxycarboxylic acids and the acylated derivatives of these esters, and has among its objects the provision of such compositions of matter and methods for their preparation. Other objects and advantages of the invention will be apparent from the description of the invention.

We have found that mixed esters of glycerol are formed on reacting glycerol, or a glycerol monoester of an aliphatic carboxylic acid, with a compound containing the acyl radical of a lower aliphatic hydroxycarboxylic acid, and that the resulting mixed glyceryl ester is converted to the corresponding acylated derivative by interaction with an acylating agent. The mixed glyceryl esters of this invention are useful as solvents, plasticizers and modifying agents for plastic compositions.

According to the present invention, mixed glyceryl esters are produced by alcoholysis on reacting a glycerol or a glyceryl monoester of an aliphatic monocarboxylic acid containing from 6 to 18 carbon atoms, with an alkyl ester of an aliphatic hydroxycarboxylic acid, preferably in the presence of an esterification catalyst. The mixed glyceryl esters thus obtained can be converted to acylated derivatives by treatment with an organic acylating agent, preferably in the presence of an acid catalyst, to form compounds of the general formula

wherein R is a member of the group consisting of

hydrogen and acyl radicals of lower fatty acids and R' is a member of the group consisting of acyl radicals of aliphatic monocarboxylic acids containing from 6 to 18 carbon atoms and the radical

wherein R has the same significance as above.

The process is applicable to glyceryl monoesters of saturated aliphatic acids such as caproic, myristic, lauric, palmitic and stearic and glyceryl monoesters of unsaturated aliphatic acids of the olefinic series such as oleic or elaidic. Suitable alkyl esters of aliphatic hydroxycarboxylic acids include, for example, the lower alkyl esters such as methyl, ethyl or propyl esters of lower, saturated, aliphatic, alpha-hydroxy monocarboxylic acids like glycolic, lactic or alpha-hydroxyisobutyric acid.

Catalysts adapted for use in the alcoholysis reaction include acidic substances such as sulfuric acid and toluene sulfonic acid and other esterification catalysts such as metal alcoholates like aluminum isopropoxide aluminum ethoxide and the like.

The hydroxyl groups of the mixed glyceryl esters are acylated by treatment with organic acylating agents preferably in the presence of a catalyst such as sulfuric acid. Suitable acylating agents include for example ketene and the anhydrides and halides of carboxylic acids such as acetic anhydride, propionic anhydride, acetyl chloride, butyryl chloride, pelargonyl chloride, crotonyl chloride, methacrylic anhydride, benzoyl chloride, phthalic anhydride and phthalyl chloride.

On producing the mixed glyceryl esters it is not necessary to utilize as the starting material purified mono-glycerides. Products containing the glyceryl monoester in admixture with di- and tri-esters, or comprising mixtures of mono-glycerides such as are present in commercial mono-glycerides derived from natural fatty materials, like coconut mono-glyceride may be used. Also, instead of using an ester of a hydroxycarboxylic acid, the corresponding hydroxycarboxylic acid can be reacted with the mono-glyceride to form the mixed glyceryl ester by esterification.

The mixed glyceryl esters and their acylation

3

products can be recovered by any suitable means, for instance, by distillation of the reaction products or by solvent extraction.

The following Examples I through VIII illustrate the preparation of the mixed glyceryl esters of our invention.

EXAMPLE I

Preparation of glyceryl dilactate tripropionate

A mixture of 184 g. (2 mol) glycerol, 624 g. (6 mol) methyl lactate and 1 g. p-toluene sulfonic acid monohydrate was heated, at atmospheric pressure, in a 2-liter flask fitted with a 2-foot Vigreux-type distilling column. Approximately 15 180 cc. methanol distilled from the reaction mixture over a period of about 4½ hours while the temperature in the still-pot was gradually raised from 118° to 172° C. Excess methyl lactate was then removed from the reaction mixture by heating the contents of the flask at about 100° C. under a vacuum of 2-3 mm. of mercury, until distillation ceased.

The viscous, straw-colored distillation residue weighing 575 g. and consisting essentially of glyceryl dilactate was cooled to room temperature and gradually treated with 780.8 g. (6 mol) propionic acid anhydride containing several drops of concentrated sulfuric acid as a catalyst. When the exothermic reaction had subsided the mixture was heated for a short time on a steam bath and allowed to cool. The acid catalyst was neutralized with 10 g. of finely powdered calcium carbonate and the propionic acid was distilled under reduced pressure yielding a distillate weighing 448 g. The distillation residue was filtered to remove the solid material and the filtrate freed of residual acidity by dissolving in benzene and washing the benzene solution with water and dilute aqueous sodium bicarbonate. The product obtained on removal of benzene by distillation consisted essentially of glyceryl dilactate tripropionate, having the following characteristics:

$N_D^{20}=1.4422$; ester equivalent 81.8; free acidity=0. The yield was 738 g. or 91% of the theoretical.

EXAMPLE II

Preparation of glyceryl dilactate tripropionate

Using essentially the procedure described in the foregoing example, glyceryl dilactate tripropionate was prepared from glyceryl dilactate obtained by ester interchange reaction on heating a mixture of 92 g. (1 mol) glycerol, 208 g. (2 mol) methyl lactate and 0.5 g. p-toluene sulfonic acid to distill off 61 cc. of methanol over a period of about 5½ hours while gradually raising the temperature of the reaction mixture from 115° to 169° C. The resulting product was acylated by interaction with 390 g. (3 mol) propionic acid anhydride containing 0.5 cc. concentrated sulfuric acid. On completion of the acylation reaction the acid catalyst was neutralized with sodium acetate. The glyceryl dilactate tripropionate obtained on removal of the propionic acid by distillation as described in Example I had a refractive index $N_D^{20}=1.4425$ and was found to be substantially free of residual acidity, therefore, not requiring further purification by washing.

EXAMPLE III

Preparation of glyceryl dilactate tripropionate

Using the procedure of Example II glyceryl dilactate tripropionate was prepared by acylation of glyceryl dilactate obtained by ester interchange reaction on heating a mixture of 92 g. 75

4

(1 mol) glycerol, 236 g. (2 mol) ethyl lactate and 0.5 g. p-toluene sulfonic acid to distill off 87 cc. of ethanol over a period of about 6 hours while gradually raising the temperature of the reaction mixture from 126° to 170° C. The glyceryl dilactate tripropionate, formed on acylation of the product thus obtained, had an index of refraction $N_D^{20}=1.4418$. The yield was 395 g. or 98% of the theoretical.

EXAMPLE IV

Preparation of glyceryl dilactate triacetate

Approximately the theoretical amount of ethanol was distilled from a reaction mixture containing 184.1 g. (2 mol) glycerol, 472.5 g. (4 mol) ethyl lactate and 4 g. of aluminum isopropoxide. An additional 4 g. of catalyst were added in the course of the reaction and a total amount of 225 cc. ethanol was obtained over a period of about 24 hours while the temperature of the reaction mixture was gradually raised to about 200° C. The filtered reaction mixture was gradually treated with an amount of acetic anhydride slightly in excess of 6 mol, containing 1 cc. of concentrated sulfuric acid as a catalyst. The catalyst was then neutralized with sodium acetate, and acetic acid, as well as excess of acetic anhydride were distilled off under reduced pressure. The distillation residue was heated for several hours on a steam bath with decolorizing carbon and filtered. The light yellowish product so obtained consisted essentially of glyceryl dilactate triacetate. $N_D^{20}=1.4421$. The yield was 460 g.

EXAMPLE V

Preparation of glyceryl dilactate triacetate

Following the procedure of Example IV and using 2 g. of p-toluene sulfonic acid as the catalyst instead of aluminum isopropoxide, the ester interchange reaction was completed in less than 4 hours. The glyceryl dilactate triacetate obtained as the final product had a refractive index $N_D^{20}=1.4450$.

EXAMPLE VI

Preparation of the diacetate of glyceryl monolaurate monolactate

Methanol was slowly distilled from a heated mixture of 274 g. (1 mol) coconut mono-glyceride (consisting mainly of glyceryl monolaurate) 208 g. (2 mol) methyl lactate and 0.5 g. p-toluene sulfonic acid. After approximately 1 mol of methanol was collected, excess of reactant and low-boiling products were distilled under reduced pressure. The distillation residue was treated with 224.5 g. (2.2 mol) of acetic anhydride containing several drops of concentrated sulfuric acid as catalyst. The acetic anhydride was added to the reaction mixture at such a rate as to avoid excessive rise of temperature. On completion of the acylation reaction the acid catalyst was neutralized with powdered calcium carbonate. Acetic acid and excess acetic anhydride were then removed by distillation under reduced pressure and the filtered distillation residue treated with activated charcoal as described in Example IV. The light amber colored product thus obtained consisted essentially of diacetate of glyceryl monolaurate monolactate. $N_D^{20}=1.4455$.

EXAMPLE VII

Preparation of the dipropionate of glyceryl monolaurate monolactate

Following essentially the procedure of the fore-

5

going example, 274 g. (1 mol) coconut monoglyceride was reacted with 312 g. (3 mol) of methyl lactate in the presence of 1 g. p-toluene sulfonic acid. The product so obtained was acylated by interaction with propionic acid anhydride containing a small amount of concentrated sulfuric acid, and the resulting dipropionate of glyceryl monolaurate monolactate washed with water and aqueous sodium bicarbonate as described in Example I. $N_D^{20}=1.4430$.

EXAMPLE VIII

Preparation of the diacetate of glyceryl monooleate monolactate

Diacetate of glyceryl monooleate monolactate was prepared by ester interchange on reacting 356 g. (1 mol) glyceryl monooleate with 312 g. (3 mol) methyl lactate in the presence of concentrated sulfuric acid as a catalyst. The resulting lactate was treated with a slight excess of acetic anhydride by the procedure described in Example VI. The final product consisting essentially of diacetate of glycerol monooleate monolactate was treated with decolorizing carbon and washed acid free. The product thus obtained had a refractive index $N_D^{20}=1.4548$ and an ester equivalent=125.2

The following Examples IX through XIII illustrate the use of the compounds of this invention as plasticizer and modifying agents for synthetic plastics such as organic cellulose esters, cellulose ethers, and polyvinyl compounds, like polyvinyl chloride, in the production of plastic composition.

EXAMPLE IX

Cellulose acetate (4.8 g.) and glyceryl dilactate tripropionate of Example I (1.2 g.) were dissolved in acetone. The clear solution was poured into a Petri dish and covered by a large watch glass. The acetone solution was allowed to evaporate slowly until a clear, dry, tough, flexible film was formed. The film characteristics remained essentially unchanged following heating at 65° C. to eliminate residual solvent.

A film having similar properties was obtained by the same procedure using glyceryl dilactate triacetate as the plasticizer.

EXAMPLE X

Polyvinyl chloride (2 g.) and acetylated monoglyceride lactate of Example VI (1 g.) were dissolved in 100 ml. dioxane by heating the mixture on a steam bath. The clear solution was poured into Petri dishes which were covered to allow slow evaporation of the solvent, and then heated for several hours at 65° C. to remove residual solvent. A clear, dry, elastic, tough film was obtained.

EXAMPLE XI

Polyvinyl chloride-acetate (2 g.) and acetylated coconut monoglyceride lactate of Example VI (1 g.) were dissolved in 50 ml. acetone. The clear solution was allowed to evaporate slowly from a covered Petri dish. A clear, dry, elastic tough film was obtained.

EXAMPLE XII

Ethyl cellulose (4.8 g.) and acetylated coconut monoglyceride lactate (1.2 g.) were dissolved in 50 ml. of a solvent mixture consisting of 80% by volume of toluene and 20% by volume of ethanol. The clear solution was allowed to evaporate slowly in a covered Petri dish. The resulting film was clear, dry, tough and flexible.

6

EXAMPLE XIII

35 g. of a copolymer containing 95% vinyl chloride and 5% vinyl acetate and 15 g. propionate of coconut monoglyceride lactate were mixed in a beaker and the mixture allowed to stand for one hour. It was then put on a 3" x 8" mill with the back roll at $300^{\circ}\pm 5^{\circ}$ F. and the front roll at $210^{\circ}\pm 5^{\circ}$ F. set at 0.005" clearance. As the material banded on the back roll the opening was increased to 0.020". When a uniform bank formed the material was cut off, rolled and the roll inserted endwise into the nip. This was repeated twice, as soon as the bank was uniform. After the third cut the mill was opened until the bank just disappeared (0.0325"), and the material cut off with the doctor blade. The milled sheet was cut to fit a 6" x 6" x 0.060" "sandwich" mold and pressed between ferrotypic plates at 300° F. and 12 T total pressure (about 640 p. s. i.) for 2 minutes, cooled and removed from the mold. The molded sheet was then conditioned 64 hours at 77° F. and 50% R. H. The product thus obtained was a dry, tough flexible sheet.

Having thus described our invention, we claim:

1. A glyceryl ester represented by a formula selected from the group consisting of

and

wherein R is the acyl radical of a lower fatty acid and R' is the acyl radical of an aliphatic monocarboxylic acid containing from 6 to 18 carbon atoms.

2. A glyceryl ester of the general formula

wherein R is the radical of a lower fatty acid.

3. The ester of claim 2 wherein R is propionyl.

4. A glyceryl ester of the general formula

wherein R is the acyl radical of a lower fatty acid and R' is the acyl radical of an aliphatic monocarboxylic acid containing from 6 to 18 carbon atoms.

5. The ester of claim 4 wherein R' is oleyl.

6. The ester of claim 4 wherein R' is an acyl radical of a fatty acid formed by hydrolysis of coconut oil.

7. The ester of claim 4 wherein R is acetyl.

8. The ester of claim 4 wherein R is propionyl.

9. A glyceryl ester of the formula

7

10. A glyceryl ester of the formula

5

11. A glyceryl ester of the formula

10

12. A process comprising subjecting a glyceryl monoester of an aliphatic monocarboxylic acid containing from 6 to 18 carbon atoms to alcoholysis by heating it with an alkyl lactate to form the monolactate of the said glyceryl monoester, and esterifying each of the hydroxyl groups of the formed monolactate of the glyceryl monoester with the same acyl group by reacting the monolactate with an organic acylating agent. 15

13. The process of claim 12 wherein the glyceryl monoester is glyceryl monolaurate. 20

8

14. The process of claim 12 wherein the glyceryl monoester is glyceryl monooleate.
